UNITED STATES PATENT OFFICE.

RUTH A. CLARK, OF TRENTON, MISSOURI.

LUNCH-BOX.

1,142,932.

Specification of Letters Patent. Patented June 15, 1915.

Application filed August 20, 1914. Serial No. 857,641.

To all whom it may concern:

Be it known that I, RUTH A. CLARK, a citizen of the United States, residing at Trenton, in the county of Grundy and State 5 of Missouri, have invented a new and useful Lunch-Box; and I do hereby declare the following to be a full, clear, and exact description of the invention, such as will enable others skilled in the art to which it 10 appertains to make and use the same.

This invention relates to a new and useful improved lunch carrier or box.

As an object of the invention it is the aim to provide a simple and efficient construction 15 of lunch carrier, for the support of dishes, bottles, fruit jars and the like.

Another object of the invention is to provide a device of this nature comprising improved and practical features of construction. 20

One of the features of construction is the provision of a dominant frame or casing having a drawer in its bottom, and an auxiliary frame fitting the dominant frame and 25 comprising top and bottom perforated shelves of an elongated contour to correspond with and fit the dominant frame, there being intermediate perforated shelves of different lengths between the top and bottom 30 shelves.

It is to be understood that the improved carrier or box and the shelves and the like upon the interior of the box may be of any suitable dimensions or shape. Said perforated shelves are held together and superimposed, by means of spacing sleeves and rods, there being nuts to hold the parts of the 35 structure together.

In practical fields the details of construction may necessitate alterations, falling 40 within the scope of what is claimed.

The invention comprises further features and combination of parts, as herinafter set forth, shown in the drawings and claimed.

45 In the drawings:—Figure 1 is a view in perspective of the improved lunch carrier or box showing the same closed, but the drawer at the bottom being opened. Fig. 2 is a view in perspective, showing the front 50 of the lunch box folded downwardly, thereby illustrating the interior plurality of perforated shelves. Fig. 3 is a detail perspective view of the plurality of perforated shelves. Fig. 4 is a detail sectional fragmentary view of the shelves and the sleeves. Fig. 5 is a transverse sectional view on line

5—5 of Fig. 1. Fig. 6 is a detail perspective view of the auxiliary frame showing the shelves of lengths different to the shelves in the other figures, and arranged differently. 60

Referring more particularly to the drawings, 1 designates the dominant frame or casing comprising the end pieces 2, the bottom 3, the longitudinal sides 4 and 5, and the top 6. A partition 7 is arranged in the lower portion of the dominant frame or casing, thereby dividing the frame or casing into a large compartment 8 and a smaller compartment 9. A suitable drawer 10 is slidably arranged in the smaller compartment 9, which drawer is provided with a space 11, for the reception of cutlery, collapsible cups, table linen, towels and the like, there being a smaller space 12, for the reception of knives, forks, spoons, sleeves, rods 75 and nuts, and the like. The division plate 13 divides the drawer into these two compartments or spaces. Suitable hooks or latches 14 are provided on the drawer for engaging the eyes 15 to hold the drawer locked. 80 Hinged at 16 is the longitudinal front side 5, the hinge 16 extending the full length of the casing, thereby preventing leakage of any fluid or the like to a great extent. The front longitudinal side 5 is provided with 85 end flanges 17 to engage upon the outside of the end pieces 2 of the casing or frame. The top 6 is hinged at 18 to the casing, said hinge extending the full length thereof, and serving the same purpose as 90 the hinge 16. The top or cover is provided with end and longitudinal edge flanges 19 and 20. The end flanges 19 engage upon the outside of the end pieces 2, while the flange 20 engages upon the outside of the longitudinal front member 5. In this manner a dominant casing or frame having tight joints at its corners is provided. The longitudinal front side 5 is provided with hooks 21 to engage eyes 22 of the top or cover 6, in 95 order to hold the parts together. The end pieces 2 are also provided with hooks 23, to engage eyes 24 of the front side 5. Connecting the end pieces 2 and the front sides 5 at its end edges are chains 25, acting to support the front side 5 when the same is opened and thrown downwardly. Suitable ventilating slides 27 are provided on the end pieces 2. Also on the end pieces are handles 28, there also being a handle 29 on 100 the top or cover 6.

An auxiliary frame 30 is provided, which

comprises top and bottom perforated shelves 31 and 32, the corners of which are connected by the vertical rods 33. These rods 33 pass or telescope through the tubular members or sleeves 34. The lower ends of the rods 33 are provided with heads countersunk in the lower portions of the tubular members or sleeves 34, to prevent scratching the bottom of the dominant frame or casing. 5

Upon the upper end of the rods 33 winged nuts 35 are threaded, thereby holding the rods in place, binding the tubular members between the heads 35^a and said winged nuts, and also binding the shelves in place. By 10

removing the winged nuts 35 the parts of the structure may be disassembled. Arranged between the top and bottom shelves 31 and 32 are intermediate perforated shelves 36 and 37. The ends 38 of the shelves 36 and 37 are mounted upon the rods 33 at one end of the auxiliary frame, and between the sleeves 34. Passing 15

through the lower shelf 32, and through the shelves 37 are rods 39, which also pass 20

shelves 36 and 37 are mounted upon the rods 33 at one end of the auxiliary frame, and between the sleeves 34. Passing through the lower shelf 32, and through the shelves 37 are rods 39, which also pass 25

through the sleeves 40, two of the sleeves 40 hold the shelves 37 spaced apart from the shelf 32 and from each other, there being nuts 41 on the rods 39, to hold the shelves 37 in place relative to the shelf 32. Short rods 43 connect the shelf 36 to one of the shelves 37, there being spacing sleeves or tubes 44 on said rods 43, and nuts 45. It will be observed, as shown in Fig. 6, that the shelves 36 and 37 may be arranged 30

differently, and furthermore it is apparent that the shelves 36 and 37 may be of different lengths than shown in the other figures, and moreover, an extra supply of shelves may be utilized, also sleeves and rods. The 35

spaces between the intermediate shelves of different lengths are for the reception of plates and of victuals and the like, while the spaces beyond the shelves of different lengths are for the reception of bottles, fruit jars and the like. 40

This form of lunch carrier or box may be constructed of any suitable material, for instance, aluminum, galvanized sheet iron, heavy tin, granite or the like, and may be 45

constructed in various sizes.

In manufacturing the lunch carrier or box, some may be constructed as shown, others made comparatively small and provided with bail handles whereby the same

may be carried easily. Others may be provided with a common ordinary lid, top or cover and constructed without sliding drawers and without drop front 5 or hinged top. 55

In Fig. 6 there is shown a series of rods 34^a, without sleeves. These rods may extend through all the shelves adjacent each of their longitudinal and end edges, to prevent large dishes and the like from slipping about in the carrier or box. These rods may be disposed farther toward the center of 60 said shelves to prevent a different or smaller sized dish or dishes from slipping. Furthermore, a series of rods 34^b may be arranged annularly, to prevent dishes from slipping, that is, such as saucers and the like, which 65 may be arranged within the annular arrangements of said rods 34^b. 70

Hangers 18^a as shown in Figs. 1 and 5, are provided, whereby the carrier or lunch box may be suspended in the pantry or other 75 suitable place. When the carrier or box is not suspended, these hangers may be turned down out of the way.

The invention having been set forth, what is claimed as new and useful is:— 80

1. In a lunch carrier, a casing, top and bottom perforated shelves to correspond with and fit the casing, intermediate shelves of different lengths between the top and bottom shelves, said intermediate shelves being 85 adjustable and spaced apart, and forming spaces of different heights and lengths at one end of the casing.

2. In a lunch carrier, a casing, top and bottom perforated shelves to correspond 90 with and fit in the casing, intermediate shelves of different lengths between the top and bottom shelves, said intermediate shelves being adjustable and spaced apart, and forming spaces of different heights and 95 lengths at one end of the casing, and a series of super-imposed sleeves for holding the several perforated shelves spaced apart from each other, rods telescoping the sleeves and passing through the shelves, and means upon 100 the rods to hold them in place.

In testimony whereof I have signed my name to this specification in the presence of two subscribing witnesses.

RUTH A. CLARK.
